UNITED STATES PATENT OFFICE.

MARTINUS VAN GELDER, OF PHILADELPHIA, PENNSYLVANIA, ASSIGNOR OF
TWO-THIRDS TO FREDERICK W. TAYLOR AND CHARLES M. TAYLOR, OF
SAME PLACE.

ROTARY ENGINE.

SPECIFICATION forming part of Letters Patent No. 668,428, dated February 19, 1901.

Application filed June 12, 1900. Serial No. 20,052. (No model.)

To all whom it may concern:

Be it known that I, MARTINUS VAN GELDER, a subject of the Queen of the Netherlands, residing in the city and county of Philadelphia, 5 in the State of Pennsylvania, have invented a new and useful Improvement in Rotary Engines, which improvement is fully set forth in the following specification and accompanying drawings.

10 My invention consists of an improved construction of rotary engine whereby an increase of speed and power is obtained.

15 The invention further consists of the structural details hereinafter fully described and claimed.

Figure 1 represents a vertical section of a rotary engine embodying my invention. Fig. 2 represents a transverse section thereof on the line xx of Fig. 1.

20 Similar letters of reference indicate corresponding parts in both figures.

Referring to the drawings, A designates the cylinder of the rotary engine, mounted upon a suitable base B. Through the side walls 25 of said cylinder and at the center thereof are bearings C for the shaft D. A steam-supply port E is situated at the outer side of the cylinder, about midway between the top and bottom, and at the bottom of the cylinder is an exhaust-port F. The pistons G are secured to the shaft and fit closely within said cylinder, thereby obviating the employment of packing between the same and the cylinder and the friction due thereto. The said pistons G consist

30 of a cylindrical portion H, having a circumferential rib J fitting within the cylinder, whereby the frictional contact between the pistons and cylinder is reduced. The front faces of the cylinders are serrated to form depressions 35 or valleys K therein, whereby increased pressure by concentration of the steam within said depressions or valleys by the angles of said serrations is obtained. The relative dimensions of said pistons and the serrations are

40 exaggerated in the drawings for the purpose of illustration, whereas in practice they would be considerably smaller. For instance, in a piston of about two and one-half or three inches in diameter said serrations would be 45 about one thirty-second of an inch deep. The

serrated front face of the piston is to be distinguished from a piston or bucket having divided faces—such, for instance, as shown in Patent No. 357,220 for a water-motor. In this patent the buckets of the wheel have two curved faces, against which the water successively impinges, but neither of which is serrated, being, in effect, two buckets with plain faces, whereas in my engine the piston has but one front face, against the entire area 55 of which the propelling medium impinges, and this face is serrated. The rear sides of the pistons are provided with inclined sides or cones L to decrease the resistance to the passage of the pistons, and suitable braces M 60 may extend between adjacent pistons.

The operation of the engine will be readily understood, as it is similar to that of rotary engines of this class. My improved construction, however, increases the speed and power 65 due to the concentration of the steam in the valley or depressions. The steam, furthermore, cannot slide so quickly to the edges of the piston, so that I am enabled to dispense with the usual packing to cause the engine 70 to run smoother and with less friction.

Having thus described my invention, what I claim as new, and desire to secure by Letters Patent, is—

1. In a rotary engine, a cylinder having inlet and exhaust ports, and a piston having a serrated front face. 80

2. In a rotary engine, a cylinder having inlet and exhaust ports, and a piston having an integral enlargement or rib fitting said cylinder, the front face of said piston being serrated, and the rear face being provided with a cone. 85

3. In a rotary engine, a cylinder having inlet and exhaust ports, and a piston having a serrated front face and a conical back face. 90

4. In a rotary engine, a cylinder having inlet and exhaust ports, a plurality of pistons, each of said pistons being formed of a cylinder and a cone, and braces connected with the cylinders and cones of adjacent pistons. 95

MARTINUS VAN GELDER.
